UNITED STATES PATENT OFFICE.

MONTAGUE H. CLEAVER AND WILBUR R. CORBIN, OF KINGSTON, NEW YORK,
ASSIGNORS TO NEVER SKID MANUFACTURING COMPANY, INCORPORATED,
A CORPORATION OF NEW YORK.

DESIGN FOR AN ANTISKID DEVICE FOR DUAL-TIRED MOTOR-TRUCKS.

43,455.

Specification for Design.

Patented Jan. 21, 1913.

Application filed September 30, 1912. Serial No. 723,264. Term of patent 14 years.

To all whom it may concern:

Be it known that we, MONTAGUE H. CLEAVER, a subject of the King of Great Britain, and WILBUR R. CORBIN, a citizen of the United States of America, residing at Kingston, county of Ulster, State of New York, have invented a new, original, and ornamental Design for an Antiskid Device for Dual-Tired Motor-Trucks, of which the following is a specification, reference being had to the accompanying drawing, forming

part thereof, which is a perspective view of the device embodying our design.

We claim:

The ornamental design for an anti-skid device for dual tired motor trucks, substantially as shown.

MONTAGUE H. CLEAVER.
WILBUR R. CORBIN.

Witnesses:

GEORGE MADDEN,
SIMON CONNOR.
